WILLIAM A. LOTZ, OF NEWARK, NEW JERSEY, ASSIGNOR TO R. NEUMANN HARDWARE CO., A CORPORATION OF NEW JERSEY.

HOLDING-CATCH FOR BAG-FRAMES.

1,032,010.

Specification of Letters Patent.

Patented July 9, 1912.

Application filed April 1, 1912. Serial No. 687,913.

To all whom it may concern:

Be it known that I, WILLIAM A. LOTZ, a citizen of the United States, residing at Newark, in the county of Essex and State 5 of New Jersey, have invented certain new and useful Improvements in Holding-Catches for Bag-Frames; and I do hereby declare the following to be a full, clear, and exact description of the invention, such as 10 will enable others skilled in the art to which it appertains to make and use the same, reference being had to the accompanying drawings, and to characters of reference marked thereon, which form a part of this specification. 15

This invention has reference, generally, to improvements in locking or holding catches for the hinged or pivotally connected frame-sections of a bag-frame; and, the present invention has for its principal object to provide a novel, neat and simply constructed locking or holding catch of the general character hereinafter more fully set forth, in which the parts of the device have been reduced to a minimum, and in which the various parts are more effectively arranged, so as to provide a strong and positively acting snap-catch for the frame-sections of a bag-frame, and the like. 20

With the various objects of the present invention in view, the said invention consists, primarily, in the novel construction of locking or holding catch for bag-frames, and the like, hereinafter more particularly set forth, and then finally embodied in the clauses of the claim which are appended to and which form an essential part of this specification. 30

The invention is clearly illustrated in the 40 accompanying drawings, in which:—

Figure 1 is a face view of a portion of a bag-frame, showing the pivotally connected frame-sections thereof, and a side view of the locking or holding catch embodying the 45 principles of the present invention; and Fig. 2 is a top or plan view of the catch, with the locking-lever thereof represented in its raised position, said view showing also in top view, portions of the two frame-sections 50 of the bag-frame in their separated relation. Fig. 3 is a longitudinal vertical section of the catch, separated from the frame-section, with the locking lever of the catch indicated in its closed position, said section being represented as taken on line 3—3 in said Fig. 55 2, looking in the direction of the arrow *x*, and said view being made on an enlarged scale. Fig. 4 is a similar sectional representation of the catch, with the locking lever of the catch, shown in its raised position; 60 Fig. 5 is a bottom view of the parts represented in said Fig. 3; and Fig. 6 is a transverse vertical section of the device, said section being taken on line 6—6 in said Fig. 3, looking in the direction of the arrow *y*. 65 Fig. 7 is a blank from which the locking or holding device of the catch is made. 70

Similar characters of reference are employed in all of the above described views, to indicate corresponding parts. 75

Referring now to the several figures of the drawings, the reference-characters 1 and 2 indicate portions of the usual forms of frame-sections of a bag-frame, or the like, the said frame-sections being provided with 80 the usual leg-members 3 and 4 which are pivotally connected by means of a rivet or pin 5, substantially as shown in Fig. 1. 85

The complete structure of the locking or holding catch is indicated by the reference-character 6, and the same consists, essentially, of a suitable shell or casing which is preferably of a rectangular configuration, and comprises a flat-top 7, a pair of end-members 8, and the longitudinally extending sides 9. At its one end-portion the said top 7 is formed with a slightly raised part, as 10, and with an opening 11, a part of said opening extending laterally across the said top, and being formed with two longitudinally extending open portions, as 12 and 13, 90 as shown more particularly in Fig. 2 of the drawings. The marginal edge-portion of the said raised part 10 is preferably undercut, as represented in said Figs. 3 and 4 of 95 the drawings, and the end-members 8 of the shell or casing of the catch are provided with downwardly extending fastening lugs, as 14, of the usual construction, and by means of which the said shell or casing is 100 secured upon the outer face of the frame-sectional in the ordinary manner. Suitably secured within the inner portion of the said shell or casing, and to the under surface of the top 7, by means of a suitable rivet 15, 105 is a spring-like engaging member 16, the same being made of sheet-metal having considerable stiffness, said member comprising a pair of suitably formed tongues or fingers 17 and 18, formed with an open space 19 110

between them, and the said tongues or fingers being suitably bent, as at 20, so as to provide two spring-members of great resiliency.

- 5 Suitably secured to the sides 9 of the shell or casing, and extending across the space formed between the said sides 9, at a point beneath the opening 11, is a pin 21 which serves as a pintle for the herein-above mentioned locking lever. This lever, as will be seen from an inspection of Fig. 7 of the drawings, is made from a flat piece of metal 22 of the general configuration shown, being provided with a pair of projections, as 10 23, each projection being integrally connected with the said flat piece of metal, extending from the longitudinal marginal edge-portions thereof, and being provided with holes or perforations 24. These projections 15 23 are bent at right angles to the plane of the said piece of metal, and the parts 25 and 26 of said piece of metal being bent at right angles to each other, the part 26 being in turn twisted so as to provide a flat portion 20 27, the planes of its faces being at right angles to the planes of the faces of the said parts 25 and 26. The said part 26 is also made of less width than the part 25, so as to provide a pair of off-sets or shoulders 28 for 25 the purposes to be presently more fully set forth. The said plate-like piece of metal 22, after it has been bent into the desired shape, is pivotally mounted by means of its perforated ears or projections upon the said 30 pin 21, between the two sides 9, the part 26 extending in a downward direction between the two tongues or fingers 17 and 18, with the flat portion 27 arranged below the plane of said tongues or fingers and extending 35 from the chambered portion of the shell or casing, and the said tongues or fingers 17 and 18 having their free end-portions resting in positive engagement upon the hereinabove mentioned off-sets or shoulders 28. 40 The upper portions of the said ears or projections 23 project into the longitudinally extending openings 12 and 13, being movably arranged therein, and the right angled part 25 extends from the opening 11, and 45 lies flat upon the upper surface of the flat top 7 of the shell or casing, as will be clearly seen from an inspection of Figs. 1 and 3 of the drawings. The said part 25 is of such length, that its free end-portion will project 50 beyond the end of the flat top 7, its said end-portion being preferably chamfered, as at 29, so as to provide a suitable lifting means for raising the said part 25 and bringing the said plate-like element 22 and its parts 55 55 into the positions indicated in Figs. 2, 4 and 60 5 of the drawings. The said part 25 is also of such thickness, that its upper flat face will lie in the same plane of the face of the raised portion 10 of the top of the shell or casing, as will be clearly evident. While 65

the said part 25 thus provides a lifting member or lever, the said flat portion 27 provides a suitable holding or locking member which enters into engagement with a latch-plate 30, or other suitable holding means, with 70 which the frame-section 2 is provided, when the frame-sections 2 and 1 have been brought into their closed relation. The normal action of the free end-portions of the spring-like tongues or fingers 17 and 18 75 being in an upward direction, the parts are held positively in the positions indicated in said Figs. 1, 3 and 6; and, the parts, when manipulated so as to permit of the separation of the frame-sections, are just as positively held in their raised relation, because of the fact that the free end-portions of the tongues or fingers still bear positively and strongly upon the marginal edges of the offsets or shoulders 28, as clearly indicated in 80 Fig. 4 of the drawings, so that the movement of the part 27 is in an upward direction and against the head of the rivet 15, and whereby the parts are securely held in their raised relation, against the accidental closing 85 90 movements of the parts, until the lever or part 24 is manipulated by the operator.

From the foregoing description of the present invention it will be clearly seen, that I have provided a novel and neat, as well as 95 a very simple and strong construction, in which the parts have been reduced to a minimum, and in which a powerful spring can be used, so as to retain the locking lever and its latch-engaging member positively either in its closed or open relation.

I claim:—

1. A catch for the frame-sections of a bag-frame, comprising a shell having means for securing said shell to a frame-section, 105 said shell being provided in its top with an opening, a locking device pivotally mounted in said shell, said locking device comprising a part 25 extending normally longitudinally along the top of said shell, a part 26 extending at right angles from said part 25, and a twisted portion connected with and extending from said part 26, said twisted portion providing a holding member, said twisted portion forming with said part 26 a pair of shoulders, and a spring-like member secured in said shell, said spring-like member comprising a pair of fingers having their free end-portions in supporting engagement with said shoulders, substantially as and for 110 the purposes set forth.

2. A catch for the frame-sections of a bag-frame, comprising a shell having means for securing said shell to a frame-section, 125 said shell being provided with a flat top, the one portion of said top being lower than the other portion thereof, and said top being provided with an opening located between the low and high portions of said top, a locking device pivotally mounted in said 130

- shell, said locking device comprising a flat part 25 extending normally longitudinally along the lower portion of said top, the upper surface of said part 25 being in the 5 same plane of the upper surface of the high portion of said top, a part 26 extending at right angles from said part 25, and a twisted portion connected with and extending from said part 26, said twisted portion 10 providing a holding member, said twisted portion forming with said part 26 a pair of shoulders, and a spring-like member secured in said shell, said spring-like member comprising a pair of fingers having their free 15 end-portions in supporting engagement with said shoulders, substantially as and for the purposes set forth.
3. A catch for the frame-sections of a bag-frame, comprising a shell having means 20 for securing said shell to a frame-section, said shell being provided with a flat top, the one portion of said top being lower than the other portion thereof, and said top being provided with an opening located between 25 the low and high portions of said top, a pintle within said shell located at a point below said opening, a locking device comprising a flat part 25, a holding member arranged at right angles to said part 25, and perforated pintle-receiving lugs at the junction of said part 25 and holding member for pivotally mounting said locking device upon said pintle, said flat part 25 extending normally longitudinally along the low portion of said top, the upper surface of said lever 30 being in the same plane of the upper surface of the high portion of said top, said holding member comprising a part 26 and a twisted portion connected with and extending from said part 26, said twisted portion forming 35 with said part 26 a pair of shoulders, and a spring-like member secured in said shell, said spring-like member comprising a pair of fingers having their free end-portions in supporting engagement with said shoulders, substantially as and for the purposes set forth. 40
- In testimony, that I claim the invention set forth above I have hereunto set my hand this 29th day of March, 1912.
